Assistant Examiner — Michelle Marquart Christeon

(57) **CLAIM**

The ornamental design for an air pressure massager as shown and described.

DESCRIPTION

1. Air pressure massager

1.1 : Perspective

1.2 : Front

1.3 : Back

1.4 : Left

1.5 : Right

1.6 : Top

1.7 : Bottom

The product indication is air pressure massager; Figure 1.1 is a perspective view of an air pressure massager, showing my new design; Figure 1.2 is a front view thereof; Figure 1.3 is a back view thereof; Figure 1.4 is a left view thereof; Figure 1.5 is a right view thereof; Figure 1.6 is a top view thereof; Figure 1.7 is a bottom view thereof; The part covered by the red color in Figure 1.1 to Figure 1.7 form no part of the claimed design. The part which is not covered by the red color in Figure 1.1 to Figure 1.7 form the part of the claimed design.

1 Claim, 7 Drawing Sheets
